UNITED STATES PATENT OFFICE

BORRIS MORRIS LEVIN, OF SAN FRANCISCO, CALIFORNIA

GENTLEMAN'S CRAVAT, FOUR-IN-HAND TYPE

Application filed April 9, 1929. Serial No. 353,746.

This invention relates to the manufacture of four-in-hand cravats. In observing the use of such cravats I have discovered that the difficulty with the proper tying of them, 5 together with short life, has been due to improper attachment of the filler in the tie with the body of the tie itself. To solve this difficulty and to give the cravat certain additional advantages, which I shall refer to, 10 I have arranged the manufacture of such cravats, which can be best understood by reference to the accompanying drawings.

Fig. 1, illustrates the cravat filler, to which I have attached by a machine basting stitch 15 a smaller piece of filler.

Fig. 2, illustrates the attachment of what is contained in Fig. 1 to the body of the cravat, turned inside out, the attachment being made by a chain stitch.

20 Fig. 3, embodies the crux of my invention. Hand stitching is inserted through the cravat and filler (as shown in Fig. 2) from both ends of the cravat, neither hand stitch, however, travelling the entire length of the 25 cravat but travelling only approximately $\frac{3}{5}$ ths of its length. Each of the hand stitches is so inserted as to cross the other at the mathematical center of the cravat.

Fig. 4, embodies everything contained in 30 Fig. 3 showing the condition of the cravat after the chain stitch shown in Fig. 2 has been removed.

Fig. 5, shows the completed cravat turned right side out and pressed.

35 The greatest advantage obtained by this method of manufacture is flexibility, which is vital for long life in a cravat and for ease in tying it. The method of basting by hand as shown in Fig. 3 permits 40 any amount of pulling or tugging at the ends of the cravat, after which the cravat immediately springs into its original shape, when the tugging and pulling is ended. Another advantage of my invention is that 45 the cravat when inserted in a collar springs into proper place by reason of the flexibility referred to.

I claim:

50 The attachment of a prearranged cravat filler to the body of the cravat by dual lines

of hand stitches, and the lines of hand stitches commencing at opposite ends of the cravat, crossing each other in approximately the mathematical center of the cravat and ending approximately three-fifths of the 55 length of the cravat from where each started.

In testimony whereof he has signed his name to this specification.

BORRIS MORRIS LEVIN.
